UNITED STATES PATENT OFFICE.

ELSWORTH DOWNING, OF COLLINS, IOWA.

HOG-RINGING CRATE.

1,301,408.

Specification of Letters Patent. Patented Apr. 22, 1919.

Application filed August 19, 1918. Serial No. 250,497.

To all whom it may concern:

Be it known that I, ELSWORTH DOWNING, a citizen of the United States, and resident of Collins, in the county of Story and State 5 of Iowa, have invented a certain new and useful Hog-Ringing Crate, of which the following is a specification.

The object of my invention is to provide a hog ringing crate of simple, durable 10 and inexpensive construction, especially designed for use by hog raisers in securing and firmly holding the snouts of hogs for convenience in placing rings therein.

More specifically it is my object to provide a device of this character into which a hog may be driven and then slowly and firmly but positively forced into position 15 with its snout projecting through the opening in the front of the device, where it may be grasped and firmly held.

A further object is to provide a device of this kind which may be readily, quickly and easily adjusted by the operator to fit hogs of varying sizes, and also to provide a device 25 in which all danger of injury to the hogs is avoided.

My invention consists in certain details in the construction, arrangement and combination of the various parts of the crate, 30 whereby the objects contemplated are attained, as hereinafter more fully set forth, pointed out in my claims and illustrated in the accompanying drawings, in which:

Figure 1 shows a side elevation of the 35 complete device embodying my invention.

Fig. 2 shows a central, vertical, longitudinal, sectional view of same taken on the line 2—2 of Fig. 4.

Fig. 3 shows a front end elevation.

Fig. 4 shows a transverse sectional view.

Fig. 5 shows a detail view of the bottom of the sliding platform and connected parts, illustrating the manner in which the ropes or cables are attached thereto.

Fig. 6 shows a detail, perspective view, 45 illustrating the upright guides on the rear of the sliding platform, and

Fig. 7 shows a detail, plan view, illustrating the means for adjusting the movable 50 sides.

Referring to the accompanying drawings, I have used the reference numeral 10 to indicate the main frame of the device. This frame is preferably rectangular in construction, with its ends open.

The hog supporting platform at the base of the frame is indicated by the reference numeral 11, and is mounted upon rollers 12 fixed to the frame 10 for movement longitudinally of the frame. Near the rear end 60 of the hog supporting platform are the upright guides 13, spaced apart far enough to permit a hog to freely walk over the platform between the guides, and a rear end gate 14 is detachably mounted in these 65 guides and capable of being removed by being lifted above the guides.

For moving the hog supporting platform either forwardly or rearwardly within the frame and upon its rollers, I have provided 70 a lever 15 preferably fulcrumed at one side of the frame, and having thereon a ratchet device 16 designed to coact with a stationary quadrant 17. Connected with the lever is a rope or cable 18, extended forwardly through pulleys 19 and attached to the hog supporting platform near its rear end, and attached to the same lever is another rope or cable 20, extended rearwardly and through the pulleys 21 and attached to 75 the hog supporting platform near its front end. Obviously, by a manipulation of this lever the hog supporting platform may be moved forwardly or rearwardly within the main frame, and by means of the ratchet 80 device and quadrant it may be firmly secured and held in any position of its adjustment.

Mounted within the frame and adjacent to the sides of the hog supporting platform, 90 are the crate side walls 22 and 23. These side walls are connected by the hinges 24 with the main frame, and normally extend upwardly and outwardly. For adjusting the incline of these crate side walls, I have 95 provided a lever 25 fulcrumed to the top of the frame and provided with a ratchet device 26 to coöperate with a sector 27 mounted on the top of the frame. Connected with the lever on opposite sides of its center, are 100 the rods 28 which extend outwardly in opposite directions and are attached respectively to the two crate sides. By this arrangement it is obvious that the upper edges of the crate sides may be tilted toward and 105 from each other and secured or locked in any position of their adjustment.

The forward end of the crate has a frame member 10^b above which is a substantially V-shaped opening near its central portion, de- 110

signed to permit a hog to project its snout through.

Beneath the said V-shaped portion is a lever 29, and attached to this lever is a loop 30 of rope or cable, which loop extends upwardly through the guides 31. This lever has at its free end a treadle 32, upon which the operator may place his foot.

In the use with this part of the device 10 and after a hog has projected its snout through the V-shaped opening, the operator grasps the loop 30 by hand and places it over the hog's snout, and then by pressing downwardly upon the treadle, firmly holds 15 the animal's snout within the loop and against the bottom of the substantially V-shaped opening.

In practical use the crate is preferably placed at the end of converging fences, 20 and the animals to be operated upon are driven into the space between these converging fences so that they will enter one at a time into the rear or open end of the crate. The foremost animal will readily enter the 25 crate by stepping upon the movable platform. Then after the animal is on the crate, the operator drops the end gate into position in its guides, thus preventing a rearward movement of the animal. The operator then grasps the lever at the side of the 30 crate, and moves the platform forwardly, carrying the hog with it, until the hog's snout projects through the V-shaped opening in the front of the crate. It is obvious 35 that in this operation it makes no difference whatever what is the size or length of the animal, as the operator simply moves the lever at the side of the crate sufficiently to project the animal's snout through the V-shaped opening, and when he releases his 40 grasp on the lever it is automatically locked and held in this position.

Then the operator places the loop or rope or cable over the animal's snout and holds 45 downwardly on the lever connected with the loop, with his foot. In this manner he can apply just the right amount of pressure to hold the animal without any danger of injury to it.

The sides of the crate may be adjusted 50 to fit and securely hold the animal by simply grasping the lever at the top of the crate and moving the sides inwardly until they firmly engage the sides of the animal. This 55 will prevent the animal from struggling to move rearwardly, and will firmly hold the animal against such rearward movement, so that the operator need put only a slight

amount of pressure on the loop over the animal's snout. This loop need only be held 60 downwardly with sufficient pressure to just hold the animal's snout, which need not be great enough pressure to hold the animal against its struggles to back out of the crate.

With my improved crate it is obvious that 65 animals may be handled very rapidly, because all of the movements of grasping, holding and moving the animals to position are done slowly but firmly and positively, so that no time need be lost on account of 70 the struggles of the animal. Furthermore, with my improved crate, animals are never injured on account of their struggles, because they are held against rearward movement by the rear end gate, which is firmly 75 but slowly moved forwardly, and then the animal's sides are held by the movable sides of the crate so that when the animal's snout is grasped by the loop there is no danger of injuring the animal's snout by the 80 pressure of the loop thereon.

I claim as my invention:

1. In a device of the class described, the combination of a suitable frame with a platform therein mounted on rollers, said platform having at its rear end at its sides, upright guide members, a removable rear end adapted to be engaged in said guide members, side crate members being pivoted at their lower ends on said main frame, means 85 for swinging said side crate members simultaneously toward or from each other, and for locking them in various positions of their movement, means for moving said platform fore-and-aft in the machine, and for locking it in various positions of its movement, said frame having at its front end a substantially V-shaped opening, a lever at the front end of said frame, and a loop on said lever.

2. In a device of the class described, the combination of a main frame, with a platform capable of fore-and-aft sliding movement in said frame, a pair of side crate members pivoted to said frame and designed 105 to be adjacent to the sides of said platform when the platform is at the forward position of movement, a lever pivoted at the top of said frame between its ends, a notched sector adjacent to said lever, a spring actuated pawl on said lever, links pivoted to said lever on opposite sides of its pivot point and pivoted to the respective side crate members.

Des Moines, Iowa, August 10, 1918.

ELSWORTH DOWNING.
